(57) **CLAIM**

The ornamental design for an earbud holder, as shown and described.

DESCRIPTION

FIG. 1 is a front elevational view of a first embodiment of an earbud holder showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front, top perspective view thereof;

FIG. 8 is a front, bottom perspective view thereof;

FIG. 9 is a back perspective view thereof;

FIG. 10 is a front, top perspective view of the earbud holder of FIG. 1, shown attached to an electronic device;

FIG. 11 is a front elevational view of a second embodiment of an earbud holder;

FIG. 12 is a rear elevational view thereof;

FIG. 13 is a right side elevation view thereof;

FIG. 14 is a left side elevational view thereof;

FIG. 15 is a top plan view thereof;

FIG. 16 is a bottom plan view thereof;

FIG. 17 is a front, top perspective view thereof;

FIG. 18 is a front, bottom perspective view thereof;

FIG. 19 is a back perspective view thereof; and,

FIG. 20 is a front, top perspective view of the earbud holder of FIG. 11, shown attached to an electronic device.

Broken lines in FIG. 10 and FIG. 20 showing an electronic device, illustrate environmental subject matter that forms no part of the claimed design.

1 Claim, 20 Drawing Sheets
